(57) **CLAIM**

The ornamental design for the patient interface gripper for ophthalmic laser surgery, as shown and described.

DESCRIPTION

FIG. 1 is a top plan view of a patient interface gripper for ophthalmic laser surgery showing my new design;

FIG. 2 is a bottom plan view thereof;

FIG. 3 is a rear elevational view thereof;

FIG. 4 is a side elevational view of the left side of the patient interface gripper for ophthalmic laser surgery oriented as in FIG. 1;

FIG. 5 is a front elevational view thereof; and,

FIG. 6 is a left rear perspective view of the patient interface gripper for ophthalmic laser surgery showing my new design.
